Primary Examiner — Omeed Agilee

(57) **CLAIM**

The ornamental design for a water flosser, as shown and described.

DESCRIPTION

FIG. 1 is a perspective view of a water flosser showing our new design where the water flosser is in a first configuration of use;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view of the water flosser where the water flosser is in a second configuration of use; and,

FIG. 10 is a perspective view of the water flosser where the water flosser is in a third configuration of use;

The broken lines in the drawings depict portions of the water flosser that form no part of the claimed design.

1 Claim, 10 Drawing Sheets
